ALFRED CHINA DE LORME, OF NEWARK, NEW JERSEY, ASSIGNOR TO SPLITDORF ELECTRICAL COMPANY, A CORPORATION OF NEW JERSEY.

INTERRUPTER MECHANISM FOR IGNITION-DYNAMOS.

1,270,385.

Specification of Letters Patent. Patented June 25, 1918.

Application filed April 20, 1916. Serial No. 92,440.

To all whom it may concern:

Be it known that I, ALFRED C. DE LORME, a citizen of the United States, residing at Newark, in the county of Essex and State of New Jersey, have invented certain new and useful Improvements in Interrupter Mechanism for Ignition-DYNAMOS, of which the following is a specification, reference being had to the accompanying drawing.

10 My invention relates to an improved interrupter mechanism for ignition dynamos commonly called magnetos, and has for its object the improvement thereof in such manner as to increase the efficiency and, at the same time, lengthen the life of the contacts and their operating parts, and to obviate certain difficulties which have heretofore arisen through the high speeds of operation of some of these parts, and to reduce sparking at the contacts.

15 The arrangement commonly employed in magnetos of the high tension jump spark type has been to provide a pair of contacts in the interrupter with a cam opening the same at the proper point on the E. M. F. wave in the generating coil, so as to render the secondary discharge circuit operative for an instant. For ordinary speeds this method has been found satisfactory, but 20 where the cam moves at high speeds, as is the case when the magneto is employed with modern 8 and 12 cylinder high speed engines, the interrupter contacts will open and close as often as 12,000 times per minute, so 25 that the lever carrying the moving contact will make about 24,000 movements per minute, or 400 per second. Owing to the rapidity with which the lever movements follow each other, the action is practically 30 continuous and a very heavy spring must be employed to secure the proper length of dwell of the contacts.

Under the conditions stated it cannot be 35 expected that the contact levers and contacts will be either highly efficient or long-lived, and I eliminate many of these objections incident to the employment of a single cam and lever by employing two levers whereby the levers need only vibrate half as 40 rapidly as one would be forced to do.

45 I am well aware that it is not new to pro-

vide an interrupter with more than one pair of contacts, or with more than one contact lever. I am not aware, however, of any invention in which a plurality of contacts or 50 levers have been arranged to operate in the manner and for the purpose of my invention, which it will be observed is applied directly to the magneto primary circuit, no 55 battery or external coil connections being necessary.

In the accompanying figure the numerals 5 and 7 denote separate brackets or anvils which are secured to the casing 1 by means of screws 22 passing through insulating 60 bushings 21. Suitable insulation 18 is placed underneath the brackets between them and the casing.

The brackets carry screws 19 and 20 having contact points 24 and 26 adapted to 65 engage the contacts 23 and 25 in the levers 4 and 6.

70 Levers 4 and 6 are pivoted at 15 and 17 on studs projecting upwardly from the base, and have in the ends opposite to the contact 75 points suitable fiber bumpers 10 and 11 adapted to engage the rotatable cam 12 mounted on the magneto shaft in any well known manner.

75 It will be observed that the levers 4 and 6 lie in the same plane, and are held on their studs by the spring clip 13, the indentations 14 and 16 in which will fit over 15 and 17. Piece 13 is normally turned to the left from the position shown in the drawing.

80 The entire casing 1 is usually movable about the cam 12 for timing purposes, and a suitable projection or handle 2 is provided whereby said casing may be connected to the usual spark advance lever. The handle may 85 be connected at any suitable point, as at 3 on the casing.

85 The angle between the center lines of the bumpers is 90 degrees, in which case, when a 180 degree cam is used the mechanism will 90 break the circuit four times per revolution of the cam.

95 29 denotes the core of the magneto winding, 27 the primary winding thereon, and 28 the secondary winding. Instead of one end 100 of the primary winding being connected to the frame of the machine denoted at G, both

ends of the primary are brought out and connected to the anvils 5 and 7, the circuit being completed through contacts 23, 24, 25, and 26 to the casing 1, which is in electrical connection with the frame of the machine.

Normally the contacts are kept closed by means of a main spring 8 and auxiliary spring 9. This is connected by screws to each lever and to the casing, so the electrical circuit is not completed through the pivots of the levers.

A condenser 36 may be connected across the primary winding, and one end of the secondary winding is usually connected to the rotating distributor finger 30 of the high tension distributor 35 and makes contacts with the points 31, 32, 33 and 34 suitably connected to the various spark plugs as indicated. 30 is timed to rotate and contact with the plug points in synchronism with the operation of the interrupter contacts.

In operation, the cam 12 being rotated, it will be noted that first lever 4 and then lever 6 will break contact, thereby opening first one and then the other end of the primary winding. This arrangement divides the work of breaking the circuit between the two levers which at high speed facilitates that function, because each lever is moved half as fast as in the case of a single lever, which would be actuated by a 4-lobed cam. It will be noted I employ a 2-lobed cam of simple construction and less liable to wear.

Having thus described my invention, I claim:

1. An interrupter for ignition dynamos comprising a pair of interrupter levers and a single cam for causing said levers to alternately and independently open the same circuit.

2. An interrupter for ignition generators comprising a pair of interrupter levers electrically connected together, and a single cam for actuating said levers to alternately and independently open the same circuit.

3. An interrupter for ignition generators comprising a casing, a pair of brackets secured to said casing insulated therefrom and from each other and carrying contacts, a pair of interrupter levers carrying contacts adapted to engage said first mentioned contacts, a single cam for operating said levers alternately and independently, and a circuit including all of said contacts in series, substantially as described.

4. An interrupter for ignition generators comprising a pair of pivoted levers, a casing supporting said levers, and a single member secured to said casing and adapted to hold said levers in place thereon, substantially as described.

5. An interrupter for ignition dynamos comprising a pair of pivoted levers, a casing

supporting said levers, a substantially V-shaped member secured to said casing and adapted to hold said levers thereon, a single cam for positively operating said levers positioned between the latter, contacts carried by said levers, and separately insulated contacts adapted to engage said lever contacts, said latter contacts connected in series in a circuit, substantially as described.

6. In an ignition dynamo, a pair of levers carrying contacts, a pair of fixed contacts engaging said lever contacts and normally insulated from each other whereby all of said contacts are in series, a supporting frame work, a generating core and primary winding thereon, and connections between said primary winding and said stationary contacts, substantially as described.

7. In an ignition dynamo, a generating coil having a primary and secondary winding, a core therefor, an interrupter body movable for timing purposes, a pair of contacts carried on said body and insulated therefrom and from each other, connections between the ends of said primary winding and said contacts, a pair of interrupter levers adapted to engage said contacts, a single cam for operating said levers, and a distributor connected to the free end of said secondary winding and adapted to be operated in unison with said cam for the purpose specified, substantially as described.

8. An interrupter for ignition systems, comprising a plurality of relatively stationary contacts, and co-operating circuit breaking pivoted levers, arranged around a central axis, a normally closed circuit, including said levers and co-operating contacts arranged therein in series, and a cam, rotatable about said axis, having a cam point adapted to close said circuit as many times as there are levers, during each revolution of the cam.

9. An interrupter for ignition systems, comprising a pair of normally closed contact devices placed around a central axis, 90° apart, a circuit in which said devices are arranged in series and a cam, having elevations 180° apart, rotatable about said axis to break said circuit by successive engagement with said contact devices.

10. An interrupter for ignition dynamos comprising a pair of interrupter levers and a cam means for causing said levers to alternately and independently open the same circuit.

11. An interrupter for ignition generators comprising a pair of interrupter levers electrically connected together, and a cam means for actuating said levers to alternately and independently open the same circuit.

12. An interrupter for ignition generators comprising a casing, a pair of brackets secured to said casing insulated therefrom and

from each other and carrying contacts, a pair of interrupter levers carrying contacts adapted to engage said first mentioned contacts, a cam means for operating said levers alternately and independently, and a circuit including all of said contacts in series.

In testimony whereof I hereunto affix my signature in the presence of two witnesses.

ALFRED CHINA DE FORME.
